UNITED STATES PATENT OFFICE

ROBERT E. READ, OF WHITE PLAINS, NEW YORK, ASSIGNOR TO INTERNATIONAL PAPER COMPANY, A CORPORATION OF NEW YORK

SHARPENING MECHANISM FOR GRINDING MACHINES

Application filed May 14, 1927. Serial No. 191,307.

This invention relates to mechanism for sharpening or burring the surface of the grinding element or stone of wood pulp grinding machines, and has reference more particularly to that type of sharpening mechanism in which a sharpening tool or burr is advanced to and held in contact with the grinding face of the revolving stone, and while in contact is caused to traverse the moving face and thereby burr or sharpen the same.

One of the objects of the invention is to provide a sharpening mechanism which, in the traversing movement of the burr, will be maintained in a straight path of travel with no liability of deviating from said path and thereby abrading the softer spots or depressions in the stone, so that the surface of the stone will be dressed squarely and uniformly across its entire extent.

Another object of the invention is to enable the attendant to control the movement of the burr to and from the stone and its pressure thereagainst, from a fixed position at the side of the stone without the necessity of standing in front of the same, whereby in the event of the bursting of the stone, the attendant will not be liable to injury by the flying parts.

A further object of the invention is to actuate the burr in its feeding movement to and from the stone, by power means, thereby enabling the attendant with the minimum of effort to expeditiously and conveniently set the burr with its proper degree of pressure on the stone for the traversing movement.

A further object of the invention is to provide mechanism in which the various operative parts are actuated by power under the complete control of the attendant, thereby enabling the sharpening operation to be effected quickly, with no effort on the part of the attendant except for the manipulation of the power controlling means, and with the maximum of uniformity of action and efficiency of operation.

With these and other objects in view, the invention consists of the improved form and construction of parts which will be described in detail in the specification to follow, and

the novel features of which will be set forth in the appended claims.

In the accompanying drawings:

Fig. 1 is a side elevation of a wood grinding machine and my improved sharpening mechanism applied thereto.

Fig. 2 is a plan view on an enlarged scale of the sharpening mechanism showing in dotted lines the adjacent portions of the frame of the grinding machine.

Fig. 3 is a front elevation of said mechanism.

Fig. 4 is a side elevation of the same as viewed from the right in Fig. 2.

Fig. 5 is a cross section on the line 5—5 of Fig. 2.

Fig. 6 is a longitudinal section on the line 6—6 of Fig. 2, on an enlarged scale.

Fig. 7 is a perspective view of the end of the burr-carrying slide and the gear train for operating said slide.

Fig. 8 is a longitudinal sectional elevation of the hydraulic cylinder for operating the burr-carrying slide, showing the piston therein and the parts operated by said piston.

Fig. 9 is an end elevation of the same, looking in the direction of the dotted arrow in Fig. 2.

Fig. 10 is a cross section on the line 10—10 of Fig. 2.

Fig. 11 is a side elevation, with parts broken away, of a modified form, of the construction shown in Figs. 8, 9 and 10.

Fig. 12 is a transverse sectional elevation of the same on the line 12—12 of Fig. 11.

Referring to the drawings:

Referring to Fig. 1, 1 designates a wood grinding machine provided with the usual wood-holding pockets 2 surmounted by cylinders 3 in which pistons 4 operate to force the wood against a rotary grindstone 5 carried by an operating shaft 6.

The improved sharpening mechanism, designated by the reference numeral 7, is suitably supported by extensions 8 and 8^a of the bed plate of the frame of the grinding machine in such position that the burring or sharpening tool 9 of the sharpening mechanism may be caused to act on the peripheral

95

100

grinding surface of the stone as will be more particularly described later on.

The feed of the burring tool to and from the stone and the pressure of the same thereagainst, is effected by means of a horizontal power cylinder 10 and a piston 11 therein, which cylinder is supported at the front of the grinding machine near one side of the same on the extension 8, and extends at right angles to the axis of rotation of the stone; and the traversing movement of the burring tool across the peripheral face of the stone is effected by a horizontal power cylinder 12 and a piston 13 therein, which cylinder extends in front of and parallel with the axis of the stone, and is supported by the bed plate extensions 8 and 8^a.

The burring tool 9 is rotatably mounted on a horizontal stud or axle supported in the forward ends of two bars 14 bolted, as by clamping bolts 15, to the opposite sides of a feed member or slide 16 movable to and from the stone, the said bolts extending through holes in the slide and bars at intervals in the length of the same, whereby the burring tool may be adjusted relatively to the slide in the direction of movement of the latter to and from the stone, in order to compensate for the reduction in diameter of the stone due to the dressing or sharpening action of the tool thereon.

The slide 16 is movably supported in guides 17 in a traversing member or carriage 18 actuated, as will be presently described, by the piston 13 of the power cylinder 12, the movement of the slide being in a direction to and from the grindstone, so that the burring tool may be moved up to contact with and held pressed against the periphery of the stone for the burring action, such movement and action of the tool being effected by the piston 11 of the power cylinder 10 through the medium of suitable gearing and driving connections best shown in Figs. 2, 3, 6, 7 and 8 and now to be described.

On reference to Fig. 8 it will be seen that the piston rod 19 connected with the piston 11 extends outwardly through the forward end of the cylinder 10 and has connected with its outer end an upwardly extending cross head 20, which cross head is connected at its upper end with the forward end of a rack bar 21 extending rearwardly and guided in a bracket 22 fixed to and extending upwardly from the rear end of the cylinder. The rack teeth 21^a, which are on the underside of the rack bar, mesh with a spur pinion 23 fixed to an operating shaft 24 mounted at one end to rotate in a bearing 22^a in the bracket 22 and at its other end in a bearing 25 on the bed extension 8^a as shown in Fig. 2, as a result of which construction and arrangement of parts, the movement of the piston rearwardly in the cylinder will rotate the pinion in the direction of the arrow, Fig. 8, and will correspondingly

rotate the shaft 24 to feed the burring tool toward the stone, and the movement of the piston forwardly in the cylinder will operate to reverse the movement of said parts.

Splined to the shaft 24 so as to slide longitudinally thereof and rotate therewith, is a bevel pinion 27 mounted in a bearing 28 in the forward end of the traversing carriage 18, which latter has formed at its forward end two arms 29 and 30, the arm 29 surrounding the shaft 24 and supporting the bearing 28, and the arm 30 surrounding the shaft and being slidable thereon. The bevel pinion 27 meshes with a bevel pinion 31 keyed to the forward end of a short shaft 32 having keyed to its rear end a spur pinion 33 formed with hub portions journaled in bearings in the forward end of the carriage at a point between the two arms 29 and 30, which pinion 33 meshes with a spur pinion 34 formed with hub portions journaled in bearings in the traversing carriage above the pinion 33, whereby the rotary motion imparted to the shaft 24 by the pinion 23, will be transmitted to the pinion 34 through the medium of the bevel pinions 27 and 31 and the spur pinion 33. The pinion 34 is threaded interiorly to screw on a fore-and-aft extending feed screw 35 which is clamped at its rear end to a lug 36 depending from the slide 16 as shown in Fig. 6, whereby the rotation of the pinion 34 by the gear train hereinbefore described, will feed the screw endwise and will impart a corresponding feeding movement to the slide 16 and the burring tool carried thereby.

From the construction described, it will be understood that the burring tool will be subject to the action of the feeding mechanism operated by the piston 11, during the entire traversing movement of the tool as controlled by the piston 13, due to the fact that in the travel of the traversing carriage, the gear train carried thereby is maintained in driving connection with the operating shaft 24 to which the bevel gear 27 is splined. As a result, the position of the burring tool in its movement to and from the grinding stone may be controlled from a single point at the side of the machine, either by means of a valve mechanism 37 for controlling the admission of pressure fluid to the actuating cylinder and thereby controlling the power means, or by means of a hand wheel 38 applied to the end of the shaft 24 for operating the feed mechanism manually.

The controlling valve mechanism 37 is connected in pipes 39 and 40 leading respectively to the opposite ends of the cylinder 10, and to an inlet pipe 41 and an outlet or exhaust pipe 42, the said valve mechanism being of the usual four-way type and operable in its different positions by a valve handle 37^a to open one end of the cylinder to the entrance of the pressure fluid, in the present instance water, and the other end of the cylinder to the outlet

or exhaust, whereby the piston may be caused to move back and forth in the cylinder and advance or retract the burring tool as desired, a pressure indicator 43 being applied to the 5 forward end of the cylinder in order to indicate the degree of pressure acting on the piston to advance the same, and consequently the degree of pressure under which the burring tool will be held against the stone.

10 In the operation of the mechanism so far described, the attendant in feeding the burring tool up to and pressing the same against the stone will adjust the controlling valve by means of the handle 37^a to a position to admit 15 the pressure to the forward end of the cylinder in front of the piston and to open the opposite end of the cylinder to the exhaust. The piston being advanced by the pressure fluid, the slide 16 carrying the burring tool will be 20 fed forwardly toward the stone and the burring tool will be engaged therewith. The further advance of the tool being thus arrested the pressure behind the piston will build up, and when the tool bears with the 25 proper degree of pressure on the stone for its proper dressing action in the traversing movement of the tool, which pressure may be determined by observing the reading of the pressure indicator, the shaft 24 is locked 30 firmly against rotation, in order to hold the tool in its set position. In the present instance this locking of the shaft is effected by means of a clamping screw 44, see Figs. 2 and 9, engaged with the bearing of the shaft 24 35 on the bracket 22, which bearing is split as at 45 so that it may be contracted by the screw and clamped firmly to the shaft and thereby hold the same against rotation. In the traversing movement of the burring tool under 40 these conditions, it will be caused to travel in a straight uniform path and will be effectually prevented from deviation from said path, so that there will be no liability of the tool abrading soft spots in the surface of the 45 stone. As a result the grinding surface of the stone will be dressed squarely and uniformly throughout its extent.

The traversing carriage 18 is mounted to slide on guideways 47 surmounting the cylinder 12, and is connected to the piston 13 of said cylinder so as to be moved back and forth thereby, by means of an operating rod 48 extending above and parallel with the cylinder and connected at one end to the side of the 55 carriage as at 49. At its opposite end the operating rod is connected to the upper end of a cross head 50, whose lower end is connected to the outer end of a piston rod 51 extending through the end of the cylinder and having its inner end connected to the piston 13 therein.

The admission of pressure fluid to the cylinder and its exhaust therefrom is controlled by a four-way valve mechanism 52 connected 60 to pipes 53 and 54 leading to the opposite

ends respectively of the cylinder, and to an inlet pipe 55 and an outlet pipe 56, the valve of said mechanism being operated by a valve handle 52^a so that the valve may be set to admit pressure to either side of the piston and open the other side to the exhaust and thereby cause the piston and consequently the traversing carriage to move in one direction or the other as desired.

It is to be noted that the controlling valve mechanism 52 is at the same side of the mechanism as the controlling valve mechanism for the cylinder 10, so that a single attendant standing at the side of the machine may control both the feeding and traversing actions of the burring tool. This I deem of importance in that the attendant is not compelled in controlling the feed of the burr to and from the cylinder and its pressure thereon, to stand in front of the stone and he is therefore not liable to be injured in the event of the stone bursting, as sometimes occurs.

In Figs. 11 and 12 are illustrated a modified form of the connections for operating the shaft 24 by the power piston of cylinder 10. In this case the rack bar 19^a is situated within the cylinder and is formed on the piston rod, and meshes with a pinion 23^a located within the cylinder at a point about midway between its ends, the piston being provided with two heads connected by the rack bar. The operation however is substantially the same as that of the parts shown in Fig. 8, the difference being that it is the forward movement of the piston within the cylinder which feeds the tool up to the stone, instead of the rearward movement of the piston as in the construction shown in Fig. 8.

While in the foregoing description and accompanying drawings the invention has been set forth in the particular detailed form and construction of parts which have been found suitable for the ends in view. It will be understood that these details may be variously changed by the skilled mechanic without departing from the limits of the invention; and further it will be understood that the invention is not limited to any particular form or construction of the parts except insofar as such limitations are specified in the claims.

Having thus described my invention, what I claim is:

1. In combination with a grinding machine provided with a rotary grinding element, a traversing carriage movable crosswise of the grinding face of said element, a slide mounted on said carriage and movable relatively thereto to and from said grinding face, a sharpening tool carried by the slide, mechanism mounted on the carriage and operatively connected with the side for moving it on the carriage, a rotary shaft extending in the direction of movement of the traversing carriage and having operative engagement with said mechanism in the different positions.

tions of the carriage, a power cylinder and a piston therein operatively engaged with the shaft for rotating it, and means for controlling the operation of the piston.

5 2. In combination with a grinding machine provided with a rotary grindstone, a traversing carriage movable in the direction of the axis of the stone, means for moving said carriage, a slide mounted on the carriage 10 and movable relatively thereto to and from the peripheral face of the stone, a sharpening tool carried by the slide, a rotary operating shaft extending in the direction of movement of the traversing carriage, means for 15 rotating said shaft, an operating gear wheel rotatably mounted on the carriage and splined to the operating shaft, and operative connections between said gear wheel and the slide for moving the same on the carriage.

20 3. In combination with a grinding machine provided with a rotary grindstone, a traversing carriage movable in the direction of the axis of the stone, means for moving said carriage, a slide mounted on the carriage 25 and movable relatively thereto to and from the peripheral face of the stone, a sharpening tool carried by the slide, a rotary operating shaft extending in the direction of movement of the traversing carriage, 30 means for rotating said shaft, a power cylinder and a piston therein operatively engaged with the shaft for rotating it, a gear wheel rotatably mounted on the carriage and splined to said shaft, operative connections 35 between said gear wheel and the slide for moving the same on the carriage, and means for controlling the operation of the piston.

40 4. In combination with a grinding machine provided with a rotary grindstone, a traversing carriage movable in the direction 45 of the axis of the stone, means for moving said carriage, a slide mounted on the carriage and movable relatively thereto to and from the peripheral face of the stone, a sharpening 50 tool carried by the slide, a feed screw connected with the slide for moving it on the carriage, a pinion journaled in bearings on the carriage and threaded interiorly to receive the feed screw, a rotary operating shaft extending 55 in the direction of movement of the traversing carriage, a gear wheel rotatably mounted on the carriage and splined to said shaft, said gear wheel being operatively connected with the pinion for rotating it, and means for rotating the operating shaft.

60 5. In combination with a grinding machine provided with a rotary grindstone, a traversing member movable in the direction of the axis of the stone, a slide mounted on the traversing member and movable relatively thereto to and from the peripheral face of the stone, a sharpening tool carried by the slide, gear mechanism operative on the slide in the different positions of the traversing 65 member to move said slide toward the stone

and set the tool in operative engagement therewith, means including a pressure cylinder mounted in fixed position adjacent one side of the grindstone for operating said mechanism, and means for locking the mechanism in its set position.

70 6. In combination with a grinding machine provided with a rotary grindstone, a traversing member movable in the direction of the axis of the stone, power mechanism for 75 operating the traversing member, a sharpening tool movable on the traversing member to and from the peripheral face of the stone, a power mechanism for moving said tool on the traversing member, said power mechanism including a fluid pressure cylinder fixed at one side of the machine relative to the traversing member, and a piston in said cylinder operatively connected with the sharpening tool for moving it on the traversing member, and means for controlling both of 80 said power mechanisms from a position at one and the same side of the machine.

85 7. In combination with a grinding machine provided with a rotary grindstone, a traversing member movable in the direction of the axis of said stone, power means for 90 moving said traversing member, a sharpening tool mounted on the traversing member and movable relatively thereto to and from the stone, mechanism on the traversing member operatively engaged with the sharpening tool for feeding the same to and from the grindstone, a rotary operating member for the feeding mechanism extending in the direction and for the full length of movement of the traversing member and with which said feeding mechanism has splined driving engagement throughout the movements of the traversing member, and power means for 95 rotating said operating member.

100 In testimony whereof, I have affixed my signature hereto.
